CLAIM

The ornamental design for a pouring attachment for containers or the like, substantially as shown and described.

DESCRIPTION

FIG. 1 is a side elevational view of a pouring attachment for containers or the like showing my new design;
FIG. 2 is a top plan view;
FIG. 3 is a bottom plan view; and
FIG. 4 is a sectional view taken on line 4—4 of FIG. 3.

*Fig. 2.**Fig. 1.**Fig. 3.**Fig. 4.*
